ELECTRIC TERMINAL CLAMP

Charles A. Danberg, Berlin, Conn., assignor to
 C. A. Danberg, Inc., Berlin, Conn., a corpora-
 tion of Connecticut

Application March 16, 1950, Serial No. 149,940

4 Claims. (Cl. 339—32)

1

This invention relates to clamps for electrically connecting cables to the terminals of electrical apparatus such as batteries, welding apparatus, and to other conductive objects, and more particularly to a clamp of the "booster" type and which has spring-pressed jaws for gripping the object with which electrical contact is to be made.

One object of this invention is to provide a clamp of the above nature in which the jaws are provided with a plurality of pairs of opposite toothed clamping recesses or surfaces formed on axes which extend in different directions, whereby the clamp may selectively grip nuts, cables and battery posts of different shapes and may be efficiently used in awkward or poorly accessible locations.

A further object is to provide a clamp of the above nature which will be simple in construction, inexpensive to manufacture, easy to apply and manipulate, compact, ornamental in appearance and very efficient and durable in use.

With these and other objects in view, there have been illustrated on the accompanying drawings two forms in which the invention may conveniently be embodied in practice.

In the drawing:

Fig. 1 is a side view of one form of the improved booster clamp, showing one way in which a battery terminal may be gripped therein.

Fig. 2 is a fragmentary side view of the same, showing the jaws as viewed from a direction opposite to that of Fig. 1.

Fig. 3 is an edge view of the same showing the jaws as they would appear when viewed from the lines 3—3 of Figs. 1 and 2, and also showing one way in which a sheet metal object may be gripped therein.

Fig. 4 is an end view showing the jaws as they would appear when viewed from the lines 4—4 of Figs. 1 and 2.

Fig. 5 is a fragmentary perspective view showing one of the jaws of the first form of the invention.

Fig. 6 is a fragmentary side view, showing jaw portions of a second form of clamp embodying the invention.

Fig. 7 is an edge view of the same as it would appear when viewed from the line 7—7 of Fig. 6, showing one way in which a battery terminal may be gripped therein.

Fig. 8 is an end view of the same showing the jaws as they would appear from the line 8—8 of Fig. 6.

Fig. 9 is a perspective view of one of the jaws of the second form of the invention.

2

Referring now to the drawings, in which like reference numerals denote corresponding parts throughout the several views, the first form of clamp is indicated generally by the numeral 10, and comprises a pair of complementary sections 11, 12, which are swingably connected at their central portions by means of a pivot pin 13.

The clamp sections 11, 12, comprises respective forwardly extending jaws 14, 15, and rearwardly extending curved handle portions 16, 17, the latter being integrally provided with a pair of opposite inwardly extending studs 18, 19, for retaining a coil spring 20 under compression between said handle portions 16, 17, whereby the jaws 14, 15 will be urged together at all times.

The clamp sections 11, 12 are made of any suitable electrically conductive material, such as cast brass, bronze, or other acid resistant alloy. The rear end of the handle portion 17 is preferably provided with an apertured lug 21 having a set screw 22 therein for connecting the end of a cable to the clamp 10.

The jaws 14, 15 are provided intermediate the lengths thereof with respective inwardly enlarged portions 23, 24 having a pair of opposed recesses 25, 25, which are formed on an axis extending longitudinally of the jaws 14, 15, and which are longitudinally toothed.

Outwardly of the enlarged portions 23, 24, the jaws 14, 15, are provided with another pair of opposed recesses 26, 26, which are also toothed, and are formed on an axis extending longitudinally of said jaws, said recesses opening outwardly through the ends of said jaws. It will be noted, however, that the recesses 26 are offset outwardly of the recesses 25, whereby the recesses 26 are adapted to define a gripping opening which is somewhat larger than the opening defined by the recesses 25.

In order to adapt the jaws 14, 15 to grip an object such as a battery post, a cable or a sheet metal article which extends laterally of said jaws, the end portions thereof are provided with pairs of longitudinally extending toothed ridges 27, 27 which are disposed at opposite sides of the recesses 26.

The end portions of the jaws 14, 15 are also integrally provided with a pair of laterally-extending opposed claws 28, 29 having a pair of opposed toothed recesses 30, 30 extending with a tapered formation cross-wise thereof, or in other words, in a direction longitudinally of the jaws 14, 15.

The extreme ends of the claws 28, 29 form toothed ridges 31, 31 which are approximately parallel to the ridges 27 and are adapted to coact

to clamp therebetween an object such as a battery terminal.

In use, a pair of clamps may be attached to the terminal posts of a run down battery and connected by cables to a source of power such as a fully charged battery. The same operator may then "step on" the starting pedal of the car and start the motor, thus eliminating the use of a second operator as was formerly required. If desired, the clamps may also be used for charging batteries or welding as they will carry a high current without overheating.

Operation of first form

In operation, the handles 16, 17 will first be manually compressed to open the jaws 14, 15 so that they may be applied over the object to be clamped and then released. As shown in Fig. 1, an upstanding battery terminal T may be clamped in the opposed end recesses 26 by the action of the coil spring 20.

If the terminal T is so located that the clamp 10 must be applied to it in an offset position, the pair of recesses 30 in the claws 28, 29 may be used to grip the terminal.

If the terminal T is in such a location that the clamp 10 must be applied at right angles thereto, said terminal may be gripped between the toothed ridges 27 of the respective jaws 14, 15; or alternatively, if the clamp 10 must be offset in a right angular relationship to said terminal, it may be gripped between the ridges 31 of said claws.

If it is desired to apply the clamp 10 to a sheet metal or other thin member such as the fender of a motor vehicle, this may be done in the manner illustrated in Fig. 3, wherein a fender F is gripped between the toothed ridges 31. Alternatively, the clamp 10 may be disposed in a horizontal position so as to grip the object between the pairs of ridges 27.

Thus it will be seen that the clamp 10 may be used for efficiently establishing and maintaining electrical contact with objects of a wide variety of shapes and sizes, and will operate properly when applied at various angles to the object to be gripped.

Second form

Referring now to Figs. 6, 7, 8, and 9, the numeral 32 indicates generally a second form of the clamp embodying the invention, said clamp having a modified jaw formation, but in other respects having the same construction as the first form of clamp 10 described above.

As shown, the clamp 32 comprises a pair of opposed complementary sections 33, 34, which are swingably joined by a pivot pin 35, and which comprise forwardly extending jaws 36, 37, and rearwardly-extending curved handle portions 38, 39.

The outer end portions of the jaws 36, 37 are curved inwardly so as to terminate in respective opposed laterally-extending ridges 40, 41, and are provided with laterally-toothed concave gripping recesses 42, 43 inwardly of said ridges. Adjacent the recesses 42, 43, the jaws 36, 37 are integrally provided with respective opposed laterally-extending claws 44, 45 having concave inner toothed recesses 46, 47, which are formed on an offset axis extending longitudinally of the jaws 36, 37.

At the opposite edges of the recesses 46, 47, the respective claws 44, 45 are formed with pairs of ridges 48, 49 which extend in a direction longitudinally of the jaws 36, 37 and which are trans-

versely toothed, whereby the second form of clamp 32 will be adapted to firmly grip thin flat objects.

Operation of second form

In use, the laterally extending claws 44, 45 of the second form of the invention will be found particularly adapted for clamping an upstanding battery terminal T as shown in Fig. 7. If it is desired to apply the clamp 32 in a horizontal position however, the terminal T may of course be gripped in the recesses 42, 43 of the jaws 36, 37.

The two pairs of ridges 48, 49 will be found useful for gripping either a battery terminal, cable or a sheet metal object extending in a direction transverse to the jaws 36, 37, while the end ridges 40, 41 will be useful for gripping objects of various shapes which are disposed in locations which are difficult of access.

While there have been disclosed in this specification two forms in which the invention may be embodied, it is to be understood that these forms are shown for the purpose of illustration only, and that the invention is not to be limited to the specific disclosures, but may be modified and embodied in various other forms without departing from its spirit. In short, the invention includes all of the modifications and embodiments coming within the scope of the following claims.

Having thus fully described the invention, what is claimed as new, and for which it is desired to secure Letters Patent is:

1. In an electric battery terminal clamp, a pair of levers pivoted together between their ends in plier-like fashion, each of said levers having an elongated handle at one end and a work-engaging jaw at its other end, a strong spring located between said handle sections for pressing said jaws together, said jaws having concave longitudinally-toothed end clamping sections and longitudinally-toothed intermediate ridges inwardly-offset from said end clamping sections to engage irregular electric terminals, and one of said handle members having a cable connecting member.
2. An electric battery terminal clamp as defined in claim 1, in which said end work-engaging jaws are also provided with laterally-toothed concave sections on both sides of said longitudinally-toothed sections.
3. An electric battery terminal clamp as defined in claim 1, in which provision is made of a pair of opposed claws integral with said jaws and extending laterally therefrom, each of said claws having concave longitudinally-toothed work-engaging sections.
4. An electric battery terminal clamp as defined in claim 1, in which provision is made of a pair of opposed claws integral with said jaws and extending laterally therefrom, each of said claws having concave laterally-toothed work-engaging sections.

CHARLES A. DANBERG.
